Attorney

UNITED STATES PATENT OFFICE.

CLARENCE L. MOORE, OF SEATTLE, WASHINGTON, ASSIGNOR TO E. O. EDWARDS, OF SEATTLE, WASHINGTON.

PIPE WRENCH.

1,404,178.

Specification of Letters Patent. Patented Jan. 17, 1922.

Application filed October 26, 1920, Serial No. 419,578. Renewed June 25, 1921. Serial No. 480,482.

To all whom it may concern:

Be it known that I, CLARENCE L. MOORE, a citizen of the United States, and residing at Seattle, in the county of King and State 5 of Washington, have invented certain new and useful Improvements in Pipe Wrenches, of which the following is a specification.

This invention relates to an improvement in wrenches of that type known as pipe 10 wrenches, and is directed particularly to a means whereby the operating pressure on the wrench serves to bind the movable jaw into closer gripping contact with the work.

In the drawings:—

15 Fig. 1 is a view in elevation of the improved wrench.

Fig. 2 is a section on line 2—2 of Fig. 1.

The improved wrench comprises a main shank 1 having rounded edges 2 and 3, 20 which for the purposes of the present invention are formed with threads 4. The upper end of the shank is formed or provided with a fixed jaw 5, having an operative serrated face 6 as is usual in wrenches 25 of this type.

The movable jaw 7 is slidably connected to the shank through the medium of upper and lower connecting straps 8 and 9. These straps are rigidly secured to the jaw, as by 30 rivets 10, and both straps encircle the shank. The upper strap 8 is of such length as to permit a movement of the upper portion of the movable jaw relative to the shank, the lower strap 9 also permitting movement of 35 the jaw relative to the shank, but to a less degree than the movement permitted by the upper strap. An operating nut 11 is threaded on the shank between the straps 8 and 9, and the upper and lower ends of the operating nut 11 are formed as conical portions 12 and 13. That portion of the movable jaw surrounding the nut 11 is cutaway 40 at 14 to receive the nut and at the upper and lower edges of such cutaway portions 45 is formed with inclined walls 15 to cooperate with the conical portions 12 and 13 of the nut.

The operative face of the movable jaw is laterally enlarged and serrated as at 16, as 50 is usual in wrenches of this type, and said movable jaw below the operative face is formed with a recess 17 to receive a pin 18, having a head 19 to bear upon the shank. A spring 20 encircles the pin within the recess,

and bears between the bottom of the recess 55 and the shank on the pin to normally exert an outward pressure on the pin.

In use as the jaws are engaged with the work, following the adjustment of the movable jaw lengthwise the shank through the 60 operation of the nut 11, it will be apparent that pressure from the handle formed by the lower portion of the shank causes the upper end of the movable jaw to move inwardly toward the shank. This movement of the 65 jaw causes a wedging cooperation between the inclined wall 15 of the jaw-recess and the conical portion of the operating nut. This wedging action tends to force the movable jaw upwardly or into closer gripping contact with the work. Of course it is understood that there is a slight relative longitudinal movement between the straps 8 and 9, and the operating nut 11. Upon release 70 of the pressure on the operating handle, the pin 18 actuates to move the jaw 7 away from the shank, thus relieving the wedging action referred to and permitting a ready disengagement of the wrench from the work. 80

What I claim is:—

1. A wrench comprising a shank terminating in a fixed jaw, a movable jaw, straps connecting the movable jaw with the shank to permit a relatively lateral movement of 85 the movable jaw, an adjusting nut threaded on the shank and operating between the straps to move the movable jaw lengthwise the shank, the movable jaw and nut being formed with cooperating inclined surfaces to force said movable jaw toward the fixed jaw in the pressure on the shank in 90 operating on the work.

2. A wrench comprising a shank terminating in a fixed jaw, a movable jaw, straps 95 connecting the movable jaw with the shank to permit a relatively lateral movement of the movable jaw, an adjusting nut threaded on the shank and operating between the straps to move the movable jaw lengthwise the shank, the movable jaw having a recess terminating in inclined walls and the adjusting nut having a conical portion for wedging cooperation with said inclined walls in operation of the wrench. 100

3. A wrench comprising a shank terminating in a fixed jaw, a movable jaw, straps connecting the movable jaw with the shank

to permit a relatively lateral movement of the movable jaw, an adjusting nut threaded on the shank and operating between the straps to move the movable jaw lengthwise 5 the shank, the movable jaw having a recess terminating in inclined walls and the adjusting nut having a conical portion for

wedging cooperation with said inclined walls in operation of the wrench, and spring means to force the movable jaw from the shank when said movable jaw is free of the wedging cooperation with the nut.

In testimony whereof I affix my signature.
CLARENCE L. MOORE.
